UNITED STATES PATENT OFFICE.

OSCAR C. BRETT, OF HUMBOLDT, KANSAS.

MAIL-BAG CATCHER.

No. 881,175.

Specification of Letters Patent. Patented March 10, 1908.

Application filed January 15, 1908. Serial No. 410,916.

To all whom it may concern:

Be it known that I, OSCAR C. BRETT, a citizen of the United States, residing in Humboldt, in the county of Allen and State of Kansas, have invented certain new and useful Improvements in Mail-Bag Catchers, of which the following is a specification.

The object of my invention is to provide novel means for receiving mail bags from moving trains.

Mail trains do not as a rule stop at all stations and usually the mail pouches for small stations are thrown to the platform from the mail car while the train is moving at high speed. This is dangerous to those standing near by and injurious to the bags which are soon worn out and often they burst open and their contents scattered. It has heretofore been proposed to provide means for receiving mail bags from a moving train, but so far as I am aware these have not gone into extensive use, owing probably to some imperfection in their construction.

According to my invention I provide means for holding mail bags at the side of a mail car which are equipped with devices for automatically releasing them when a train arrives at a mail station and which are constructed to hold the bags steady against the influence of the wind or pressure of air while exposed thereto. At the station I provide means for causing the bags to be automatically detached from the car and for receiving and carrying them with a minimum amount of concussion or friction to a receptacle for safe keeping.

The mail bag receiving device is constructed to receive and deposit bags from trains moving in either direction on a single track, some of the parts being adjustable for this purpose while other parts remain in a fixed position.

In the accompanying drawings, Figure 1 is a perspective view of my improved mail bag receiving and depositing device showing its relation to a railway track and it also indicates in dotted lines a car with my improved bag holder and the means for detaching the bag from its holder and depositing it in the receiving device. Fig. 1^a is a plan view of the same. Fig. 2 is a plan view of certain parts of the receiver and the depository for the bags. Fig. 3 is a plan view of the improved mail bag holder showing how it is

attached to a car and showing also how its catch is automatically operated to release a bag. Fig. 4 shows a section of the devices shown in Fig. 3 with the catch operating post shown in elevation. Fig. 5 is a perspective view of the hanger which suspends the bag in its holder. Fig. 6 is a detail view in section of the devices employed for locking the adjustable part of the receiver in its adjusted position.

A indicates the track of a single track railway and B indicates partly by dotted lines a car provided with a mail bag holder C from which the bag X is suspended.

D, D', are tripping posts provided with arms, d, d', which engage the catch of the bag holder for releasing the bag.

The receiver comprises two stationary troughs E, E', a pivoted chute F and a depository G. The holder C comprises two parallel bars e connected at their outer ends to a ring e' and provided intermediate their opposite ends with a cross bar or handle e². The inner ends of the bars e are bent as indicated at e³ adapting them to engage slots in metallic plates e⁴, secured to the floor of the mail car a short distance from the door. The arms are also provided with lugs e⁵ which engage corresponding holes in the plates e⁴ placed nearer the car door than the plates e⁴. By these devices the holder may be held firmly in position or readily removed from delivering position and stored within the car when desired. From the ring e' is suspended a wind shield H shown as consisting of a sheet metal cylinder of sufficient size to accommodate any size mail bag, of sufficient diameter to prevent the bag swaying much and long enough to protect it from the wind or pressure of air caused by the rapid movement of the train. A catch bar I is pivoted to the ring e' at i and extends diametrically across the ring and from its pivotal portion projects an operating arm i' adapted to engage the arm or bracket d or d' on the tripping post D or D'.

The bag X is suspended within the shield by means of a hanger J which may be attached to the bag in any suitable way and which has a slotted head j which engages the catch bar in the manner indicated. The arrangement is such that when the arm i' encounters an arm d of a tripping post, the catch bar will be turned on its pivot and dis-

engage itself from the hanger and allow the mail bag to drop into one of the troughs E or E'.

Each receiving trough may be constructed 5 in any suitable way but preferably of wood covered with sheet metal. The two troughs are similar in construction. Each consists of a long, flat, horizontal portion e, closed at the bottom and on 3 sides and it is open 10 at the top and at one end. The end-piece e', and the side-pieces e² need not be very high but the horizontal portion of the trough is preferably from 20 to 30 ft. long. From the open end of the horizontal portion e rises 15 the inclined portion e³ of the trough, which not only inclines upwardly but also sidewise away from the track. This portion of the trough is closed at the bottom and has opposite side-pieces e⁴ which are preferably some- 20 what higher than the side-pieces e². This inclined portion of the trough is open at the top and at each end and at its upper end it is provided with a cylindrical portion e⁵ adapted to register with the mouth of the adjust- 25 able chute F. The chute F and the troughs E, E' may be supported in any suitable way. The portions e of the troughs are arranged close to the tripping posts D, D'. The adjust- 30 able chute F and the upper ends of the troughs E, E' are supported in a suitable frame K. The chute F has a large flaring end adapted to register with the upper end e⁵ of either of the troughs E, E'. It gradually tapers from its larger end or mouth towards 35 the opposite end of its horizontal portion and midway between its ends it is encircled by a band or ring f to which it is firmly connected and which is mounted on a vertical pivot f' in the frame K, the arrangement being 40 such that the chute may be swung around on its pivot through an arc of 180° so that its mouth may register with the delivering end of either of the troughs E, E'. The chute has an outer section F' which is joined to the 45 horizontal or inner section in the manner indicated in Fig. 6 or in any other suitable way which will permit it to be adjusted or turned around a vertical axis and it carries a locking device f² by means of which it may be 50 locked to the lower part of the chute and held firmly in its adjusted position. The delivering section F' of the chute is curved upwardly and laterally as indicated in Fig. 1 and in Fig. 2 in order that it may deliver 55 properly to the depository G when set in either of its positions. In order to lock the chute in either of its two adjusted positions, I provide a catch M indicated in Fig. 2, and also in Fig. 6. This may be of any suitable 60 construction but as shown in Fig. 6 comprises a spring dog m which is adapted to engage a suitable socket in either of the seg- 65 mental plates, N. By these devices the adjustable chute is locked in either of its two

After passing through a trough and through the chute the bag is delivered to the depository G, which is shown as consisting of standards O supporting a housing P, the bottom of which consists of wire netting Q, or it may be of other suitable material. The 70 housing is provided with a door R to permit access to the depository from one end of the housing.

It will thus be seen that mail bags from 75 fast moving trains may be received and deposited without the necessity for the presence of an attendant at the receiving station and with very little care or trouble to the mail agent on the train. It is necessary for 80 the agent on the train to merely place the holder in position with the bag in its shield and set the catch bar at the proper angle. No further attention is then required because as soon as the train arrives at the station the 85 catch bar is tripped automatically, the bag falls into the outer end of one of the troughs, slides along the horizontal portion thereof with very little friction and then passes up the inclined portion, enters the tubular 90 chute, passes therefrom and is delivered to the housed depository. The inclination of the troughs and the chute and the curvatures given thereto is such as to break the force or momentum of the bag and yet the bag is 95 subjected to comparatively little friction and its life is thereby prolonged. All the parts may be made substantial and durable and will require but little repair.

I claim as my invention:

1. A mail bag deliverer and catcher comprising a holder for the bag projecting from a car, a catch on the holder, means for operating the catch to release the bag, a trough into which the bag drops and a 105 pivoted chute registering with the delivery end of the trough and having a discharge member adjustable about a vertical axis through which the bag is delivered.

2. The combination with a holder for suspending a mail bag from a railway car, of a wind shield carried thereby, a catch for suspending the bag from the holder within the shield, and an arm projecting from the catch for operating it to drop the bag.

3. The combination with a holder for suspending a mail bag from a car, of a wind shield carried by the holder, a catch for detachably suspending the bag within the shield, and means engaging the catch for 120 releasing the bag.

4. The combination with a holder for suspending a mail bag from a car, of a wind shield carried by the holder within which the bag is suspended, a catch bar pivoted to the 125 upper end of the holder, and a hanger connected with the bag and detachably connected with the catch bar.

5. A holder for suspending a mail bag from a car comprising parallel arms having bent 130

inner ends, a cross bar or handle connecting the arms, a ring connected with the outer ends of the arms, a cylindrical wind shield depending from the ring and a catch bar 5 pivotally connected with the ring.

6. A mail bag receiver comprising a trough having a long, horizontal portion from which it inclines upwardly, a pivoted chute the mouth of which is adapted to register with the upper end of the trough, and to which is pivotally connected a discharge portion curved upwardly and outwardly for the purpose specified.

7. The combination of the two troughs having upwardly inclined portions, a chute pivotally mounted between the troughs and having a mouth adapted to register with the upper end of either trough and a pivoted section of the chute curved upwardly and outwardly for the purpose specified.

8. The combination with a depository for mail bags, of two troughs having upwardly inclined portions, a tubular chute pivoted

between the troughs and having a mouth adapted to register with the upper end of either trough, means for locking the chute in either of its adjusted positions and a chute section pivotally mounted on the chute having a laterally projecting portion extending to the depository, and means for locking the chute section in place.

9. The combination of two troughs, each having a long, horizontal portion connecting with a portion inclined upwardly and outwardly, a chute pivotally mounted between the troughs and having a mouth adapted to register with the upper end of either trough and a depository with which the chute communicates.

In testimony whereof, I have hereunto 40
subscribed my name:

OSCAR C. BRETT.
